UNITED STATES PATENT OFFICE.

FRANK W. SHUELL, OF DETROIT, MICHIGAN, ASSIGNOR TO EVERHOT HEATER COMPANY, OF DETROIT, MICHIGAN, A CORPORATION OF MICHIGAN.

WATER-HEATING APPARATUS.

Application filed January 7, 1924. Serial No. 684,878.

The invention relates to water heating apparatus of that type in which the heating burner is arranged beneath the tank containing the water. With such constructions where the tank is cold, the condensation of moisture thereon together with absorbed gaseous products of combustion will produce a corrosive agent. This in turn will react upon the tank so that the drippings, if they fall upon the burner, contains matter which frequently obstructs the gas discharge orifices. It is the object of the present invention to form a simple means for protecting the burner from such drippings, said means also performing another desirable function, as hereinafter set forth.

In the drawings:

Figure 1 is a vertical section through a water heater to which my improvements are applied;

Figure 2 is an enlarged section of a portion of Figure 1.

As shown, A is a water tank, B a surrounding jacket therefor, and C a gas burner within said jacket and beneath the tank. It is usual to form the tanks with convex bottom headers so as to produce a stream line surface for the gases of combustion to pass over. This, however, causes any condensation on the walls of the tank to flow towards the center of the bottom and to drip therefrom onto the burner. With my improved construction I have changed the form of the tank by providing a substantially flat portion D directly above the burner and surrounding this portion by a bead or annular depression E, which is pressed in the metal of the head. Thus any condensation collecting on the side walls of the tank and flowing down therefrom upon reaching the bead E will drop off outside of the burner.

The bead E is utilized for the further function of forming a drain trough from which the water can be drained from the tank. To this end I connect the drain conduit F with the tank so as to intersect this groove and as the bottom portion D is flat or substantially so, all of the water within the tank will flow into the groove.

The heads for the tank are usually made of pressed sheet metal and by suitably forming the dies the bead E is formed in the same operation which forms the head. Thus without increasing the cost of manufacture, I have obtained a construction having the com-

bined advantage of protecting the burner and forming a convenient means for draining the tank.

What I claim as my invention is:

1. In a water heater, the combination of an outer casing, a gas burner, a water storage tank spaced within said container forming an annular flue passageway, said tank having its entire lower end spaced a substantial distance above said burner and adapted to deflect the flame laterally to communicate with said annular flue and a depressed portion extending slightly below the remaining portions of said tank arranged to direct the drippings of condensed water away from said burner, said depressed portion being of such small height as to prevent any appreciable downward deflection of the combustion gases before entering the annular flue.

2. In a water heater, the combination with a gas burner, of a water storage tank having a lower head formed of sheet metal, the entire area of which is located a substantial distance above said burner, said head having a substantially flat area directly above the burner and an annular pressed out bead surrounding said flat area and depending only slightly below the same to cause the condensation to collect thereon whereby drippings therefrom will clear the burner.

3. In a water heater, the combination with a gas burner, of a liquid container having a lower head spaced a substantial distance above said burner, and means spaced radially inward from the marginal portions of said head and spaced radially outward from the portion of said head directly above the gas burner for directing the drippings of condensed moisture away from the burner.

4. In a water heater, the combination with a gas burner, of a liquid container having a lower head spaced a substantial distance above said burner, said head having a downwardly pressed annular portion forming a drip bead spaced radially inward from the marginal portions of the head and lower than and surrounding the area directly above said burner.

5. In a water heater, the combination with a gas burner, of a water storage tank having a lower head spaced a substantial distance above said burner, said lower head having the area directly above said burner of non-convex form and also having a de-

pending portion surrounding said area and extending lower than the same for directing drippings of condensed moisture away from said burner said head having a convex peripheral portion surrounding said depending portion.

6. In a water heater, the combination with a gas burner, of a water storage tank having a lower head spaced a substantial distance above said burner, said lower head hav-

ing a non-convex area directly above said burner and having a downwardly pressed annular portion forming a drip bead lower than and surrounding said non-convex area, said annular depressed portion also forming a groove within said container, and a drain connection communicating with said groove.

In testimony whereof I affix my signature.

FRANK W. SHUELL.
